United States Patent

Des. 238,152
Patented Dec. 23, 1975

238,152

COMBINED WATCH DIAL AND HANDS THEREFOR

Lester E. Rubenstein, 100 E. Hartsdale Ave.,
Hartsdale, N.Y. 10530

Filed Aug. 8, 1974, Ser. No. 495,806

Term of patent 3½ years

Int. Cl. D10—02

U.S. Cl. D10—33

FIG. 1

FIG. 2

FIG. 1 is a front elevational view of a combined watch dial and hands therefor showing my new design, the rear being plain and unornamented;

FIG. 2 is a typical side elevational view thereof;

Portions of FIG. 1 are shaded for color.

I claim:

An ornamental design for a combined watch dial and hands therefor, as substantially shown and described.
